ART OF STAPLING

Frank R. Curtiss, New Haven, Conn.

Application Dec. 19, 1933, Serial No. 703,032

14 Claims.

(CL 1-49)

This invention relates to new and useful improvements in staple driving means and staples therefor.

An object of the invention is to provide a means whereby folded materials may be stapled through their inner folds without having the staple exposed through their outer or forward fold or folds.

A more specific object is to provide a staple driving means including means whereby the cuffs of trousers may be stapled rather than sewed in place, the staple being concealed so as not to show at the outer side of the trouser cuff.

Another object is to provide a staple driving means including means for preventing the clogging of staples in the raceway of the machine.

A further object is to provide an improved staple particularly adapted to be tightly closed or clinched.

An additional object is to provide a machine adapted to receive and drive such staples.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a side elevational view showing a complete staple driving machine having the features of the invention incorporated therein;

Fig. 2 is a front elevational view illustrating the operation of positioning the machine on a trouser cuff preliminary to stapling the same in place;

Fig. 3 is a bottom plan view of the anvil portion or upper jaw of the machine;

Fig. 4 is an enlarged transverse sectional view through the needle;

Fig. 5 is a greatly enlarged plan view of the forward or penetrating end of the needle;

Fig. 6 is a transverse sectional view on an enlarged scale and illustrating the relationship of the parts;

Fig. 7 is a view somewhat similar to Fig. 6 but showing the parts at the end of an operation stapling a trouser cuff in place;

Fig. 8 is a sectional view through a stapled trouser cuff showing the staple in place;

Fig. 9 is a perspective view of a strip of the improved staples;

Fig. 10 is an enlarged sectional view taken substantially along the line 10-10 of Fig. 2; and

Fig. 11 is a similar view but showing the parts at the end of a staple driving operation and before they have returned to their normal positions.

Referring in detail to the drawing, the improved machine is disclosed as of the plier type although it is to be understood and later will become apparent that the features of the invention are applicable to other types of staple driving machine and that certain features of the invention are applicable irrespective of whether the machine is of the plier type and irrespective of whether the machine simply drives the staple or includes an anvil means against which the staples are clinched. The machine shown includes a central housing member 12 which at its forward end carries a head 13 and the member 12 is mounted for movement about a pivot 14 which pivot also mounts and pivotally connects members 15 and 16, the rear portions of which form handles 17 and 18. The forward portion of member 15 comprises an operating member 19 while the forward portion of member 16 comprises a jaw 20 comprising or mounting an anvil means 21.

Within the member 12 there is arranged a staple guide bar 22 here disclosed as in the form of an inverted U and a strip of staples 23 (later to be more fully described) is arranged on this guide bar in positions spanning the lower open side thereof and the staples are fed along the bar by means of a spring pressed follower 24 which follower is slidably mounted on a rod 25 and normally urged forwardly therealong as by a coil spring 26. Obviously, follower 24 also spans the lower open side of the guide bar 22 and being U-shaped in transverse section engages the rearmost staple of strip 23 and feeds the staples along the bar toward the forward end thereof.

At its rear end the rod 25 may be connected with a head 27 having a bayonet slot connection with the member 12 as shown in Fig. 1. Due to this bayonet slot connection the rod and associated parts may be locked in the member 12 or may be removed therefrom to permit of the insertion of a new staple strip after which the rod, follower and the like are replaced in the machine.

The guide bar 22 at its forward end stops at one side of a raceway 28 in the head 13 and through which raceway is operable a plunger 29 designed for driving staples. It will be understood that the staples are fed one at a time into the raceway.

and that when a staple is in the raceway and plunger 29 is operated it will drive the staple. Actually the forward end of the staple strip is projected into the raceway a distance equal to 5 the thickness of one staple and the width of the raceway is such that two staples cannot be fed into it in side by side relation. Therefore, it will be understood that as the plunger is operated through the raceway it cuts or severs the first 10 staple from the strip 23 and drives such staple through the raceway.

When papers or other materials are to be 15 stapled together they are inserted into the space 38 between the head 13 and the anvil 21 and on 20 the handles 17 and 18 being squeezed toward one another the handle 17 and the member 12 maintain the relationship shown while the handle 18 moves about the pivot 14 to bring the anvil toward the head 13. On further pressure being applied the handle 17 rocks about its pivot 14 relative to the member 12 and the handle 18 (the latter two being in engagement through their anvil 25 means 24 and head 13 make no further relative movement) and as the handle 17 approaches the member 12 the said handle operates the plunger 29 to drive a staple through the raceway 28. The operation of the plunger by handle 17 results from the fact that the projection 19 of said handle extends through an opening 31 in the plunger and 30 movement of the handle and its projection therefore necessarily results in movement of the plunger. Should a staple become clogged in the raceway, movement of the member 12 in the direction of the handle 17 will result in the head 13 of 35 said member being carried away from the anvil means 24 and will further result in operation of the plunger through the raceway to clear the same.

Anvil means 21 includes the bracket-like member 32 secured to the jaw portion 28 as by bolts or rivets 33 and said member 32 carries a relatively heavy cross piece 34 extending transversely of the jaw 28 and head 13 or laterally in each direction of said jaw and head. As will later more 45 fully appear this relatively heavy member 34 comprises a guard and guide and backing up piece and is arranged in the path of movement of the plunger 28.

A penetrating instrument or needle-like means 50 35 is arranged at the plunger side of the member 34 and as shown the needle 35 is of substantially the length of the member 34 and extends laterally to each side of the head 13 and at one end is enlarged and secured to the member 34 as by a pair of rivets or the like 36. Here it will be noted that needle 35 should be secured to the member 34 or its equivalent at at least two points to prevent pivotal or turning movement of the needle relative to the member.

60 At its end opposite its secured end the needle 35 is provided with a rounded point or penetrating end 37 (see particularly Fig. 5) and the needle is preferably of greater width than thickness and its edges are rounded as shown at 38 (see Fig. 4). The object of this particular construction of 65 needle will later be fully set forth. Intermediate its ends and in fact in alignment with the plunger 29 the needle is provided with anvil or clinching depressions 39 deepest at their outer or remote ends and gradually of less depth as they approach one another and these depressions serve to turn the ends of the legs of a driven staple toward one another to clinch the staple.

If the needle is of such thinness (and the thinness of the needle is a desirable attribute, as will 75

later appear) that the formation of the clinching depressions 39 results in off-setting of portions of the needle through its bottom wall then the guide and guard and backing up member 34 may be provided with similar shaped depressions 40 to accommodate the offset material of the needle. This member 34 extends slightly beyond the pointed or sharpened end of the needle and has its outer end portion 41 curved or turned outwardly away from the needle to provide a funnel-like entrance 42 between its free end and the free or penetrating end of the needle as best shown in Figs. 2 and 7.

It is noted that the staples of the strip 23 are generally U-shaped but that each individual staple has its connecting portion inwardly bowed whereby the connecting portion of the strip is in effect provided with a grove or channel 43. As best disclosed in Fig. 6 this inwardly bowed portion of the staple strip enters the open side of the guide bar 22 and in said figure the staple is designated 44 and it will be noted that its legs are arranged at the outer sides of the guide bar and that its bowed portion 45 enters the open side of the guide bar. A ward 46 shaped as is the connecting portion of the staple is arranged at the open side of the guide bar and the curved portion of the ward enters or accommodates the groove or channel 43 of the staple strip whereby the strip is retained in position on the guide bar and the insertion of the wrong type of staple 30 strip into the machine is prevented.

The lower or staple engaging edge 47 of the plunger 29 is also shaped to correspond with the upper or outer surface of the connecting portions of the staples. When driving a staple the plunger 35 engages the outer surface of the connecting portion of a staple as best shown in Fig. 7 and as the staple is driven, the anvil recesses 38 of the needle 35 turn the ends of the staple legs toward one another and direct them slightly inwardly or 40 in the direction of the connection portion of the staple. This results in a tendency of the staple to form a pair of loops when the staple is fully and properly clinched.

Since the shaped staple engaging edge 47 of 45 the plunger enters the depression in the connecting portion of the staple the said connecting portion is prevented from collapsing inwardly and permitting movement of the portions of the staple legs, adjacent the connecting portion 50 thereof, inwardly toward one another. Further, this shaped edge of the plunger prevents the bowed portion or depressed portion of the connecting part of the staple from bulging or moving outwardly in a direction to straighten itself 55 when it contacts with the material being stapled and this bowed portion 45 being bowed inwardly is almost in engagement with the ends 48 of the legs of the staple when the staple is clinched. This is fully shown in Fig. 7 wherein it will be 60 noted that the staple legs being directed or inclined inwardly and the connecting portion 45 being bowed inwardly the staple when clinched is almost in the form of a pair of closed loops and accordingly securely connects any objects or material through which it has been driven.

In the initial movement of the handles 17 and 18 toward one another a spring 49 connecting the handle 17 with the jaw 28 yields to permit such jaw to approach the housing 13. As the final 70 pressure is applied to operate the plunger a spring 50 is compressed. At the end of the operation or when the staple has been driven the handles are released and the springs 49 and 50 serve to return the handles to their normal relative posi- 75

tions. As the handles return to their normal positions the extension 19 of member 15, being rigid or integral with the handle 17, returns the plunger to normal position.

5 At the present time the cuffs or trousers are sewed or stitched in place by stitches passed through the cuffs at opposite sides of the trouser legs. The machine of the present invention is capable of tacking up the trouser cuffs so that 10 they may be fastened more cheaply and more expeditiously than is possible by sewing. When dry cleaning trousers, the threads holding the cuffs up are cut so that the cuff will be cleaned and after the cleaning operation it is necessary 15 to resew the cuff in place. Usually those performing the actual cleaning operations are not tailors and not infrequently the garments are returned to small establishments, which serve as collection agencies for cleaning houses and have no 20 cleaning plant of their own, with the cuffs still loose and such agencies must sew the cuffs in place. The present means is such that the cuffs may be stapled in place by staples inserted from the inner side and which do not extend entirely 25 through the cuff and are not visible at its outer side.

Generally a trouser cuff is made up as shown in Fig. 8 wherein a portion of a trouser leg is shown at 51 and it is noted that the material 30 thereof is doubled on itself at 52 and carried upwardly providing a layer of material 53 at the upper end of which the fabric is again doubled on itself at 54 providing an outer layer of material 55 and at its lower end or at the lower 35 end of the layer 55 the material is doubled on itself as at 56 and carried upwardly at the inner side of the trouser leg as at 57. The upper edge of the portion 57 is usually sewed to the layer 51 of the material. The cuff, then, is generally designated 58 in Fig. 8 and comprises the doubled 40 up material forming the layers 53 and 55.

To tack the cuff 58 in place after it has been folded into the proper position the cuff, and, in fact, the entire lower end of one side of the trouser leg is inserted into the space 30 between 45 the head and anvil of the machine with the head of the machine at the inner side of the trouser leg. The needle 35 is then passed through the outer layer 55 of the cuff being introduced as shown in Fig. 2. From that figure it will be noted 50 that the member 34 acts as a guard to limit penetration of the cuff by the needle and also acts as a guide. The needle having been introduced through the outer layer of material 55 of the cuff, the entire machine is shifted laterally 55 so as to bring the needle between the outer layer of material of the cuff and the raceway and plunger in the head 13. The parts are shown so positioned in Fig. 7.

60 The staple may now be driven and, of course, the free ends of the legs of the staple will penetrate the two inner layers 51 and 53 of the cuff and then engage the needle 35 in the anvil depressions 39 thereof. As the staple is driven its legs are turned inwardly toward one another and into a position inclining toward its connecting portion as fully shown in Fig. 7 and as described above. From the Figs. 7 and 8 it will be clear that the staple has not penetrated the outer layer of material 55 of the cuff and that 65 the staple will not therefore be visible from the outer side of the trouser leg. The stapling operation is repeated at each side of the cuff so that the staples take the place of the usual threads 70 employed for tacking the cuff in place.

Since the needle 35 has a rounded point 37 it will not cut a thread if it directly engages the same but will force the thread to one side or the other. Further, as the edges of the needle are rounded at 38 the needle will force apart the 5 threads as the needle is passed through the outer layer of material of the cuff and will not cut any of the threads of such material. This is an advantage and further to prevent rupture of any of the threads it is desirable to have the needle 10 as narrow and as thin as possible and for this last reason the needle is mounted to extend laterally or cross-wise of the machine head so that the anvil depressions 39 may extend longitudinally 15 of the needle and it will not be necessary 20 to make the needle of the considerable width which would be necessary if said depressions extended transversely of the needle as would be the case if the needle extended forwardly or from the front of the machine. However, this last structure could be used in some instances.

It will be understood that normally the needle must be spaced from the member 34 for at least a distance equal to the thickness of the material through which the needle must penetrate and 25 which the needle prevents the staple from passing through. When the clinching pressure is applied to clinch a staple between the plunger and the needle, the needle being relatively light as above explained, yields or springs and shifts into a 30 position against the guard and backing up member 34 as shown in Fig. 7. Since the needle is secured at its enlarged end and since this end is spaced laterally from the anvil portion of the needle it will be apparent that the needle may 35 readily so yield as to bring its anvil portion flat against the member 34 without breaking or fracturing the needle so that on the parts being released the needle resumes its normal position.

The present staple driving machine also 40 includes means automatically passed through the lower or delivery end of the raceway at the end of each stapling operation so as to clean out or remove from the raceway any staple which may have become clogged therein. As disclosed this 45 means includes an arm 59 pivoted between its ends to a pair of ears 60 as by pin or rivet 61. One end of this arm is received in an opening 62 in the plunger 29 and to the other end of the arm there is pivoted as at 63 one end of a dog 64. A 50 spring 65 normally maintains the dog 64 in a position with its end 66 extending across the lower or delivery end of the raceway 28. The dog is shown in its normal position in Figs. 1, 2, and 10.

As the plunger is operated to drive a staple 55 through the raceway it, of course, carries the inner end of the arm 59 downwardly with it due to the fact that such end of the arm is disposed in the opening 62 in the plunger. As the inner 60 end of the arm is carried by the plunger the outer end thereof swings outwardly away from the head 13 of the machine and shifts the dog 64 from the position of Fig. 10 to that of Fig. 11 and in the latter figure it will be noted that the spring 65 is functioning to maintain the end 66 of the dog 65 against the plunger 29. When the staple has been driven or as the plunger is returned to normal position it acts to swing the arm 59 in a reverse direction about its pivot and shift the dog 64 downwardly of the raceway toward the delivery 70 end thereof. Since the spring 65 constantly influences the dog the end 66 of the latter enters the raceway immediately it passes off the staple engaging end of the plunger and extends across the raceway to engage any staple clogged therein. 75

Obviously, the dog will operate to clear the raceway or force a clogged staple out of the delivery end portion of the raceway.

From the foregoing description taken in connection with the accompanying drawing it will be apparent that with the improved staple driving machine staples may readily be driven through the inner layers of the material of a trouser cuff or the like and clinched without having the staples pass through or be exposed at the outer side of the outer layer of material. While the invention has been described with relation to tacking a trouser cuff in place it will be appreciated that the invention may be used in any connection where it is desirable to insert an anvil through a layer of material to clinch staples and prevent them passing through such material. Further, owing to the particular construction of the improved staple and driving plunger and anvil the staple may be tightly clinched forming two substantially closed loops as best illustrated in Fig. 7.

Also, the ward 46 prevents the wrong type of staple being inserted in the machine and maintains the proper staple on the guide bar and the dog 64 and means for operating the same serve to clear the raceway at the end of each stapling operation. It will, of course, be understood that it is only occasionally that a staple becomes wedged or clogged in the raceway. When this occurs, the operator usually tries to force the machine with the result that it is clogged worse than ever. With the present means including the dog 64 the raceway is automatically cleaned as the parts return to normal position and after each operation so that if a staple has wedged in the raceway it is removed therefrom without any conscious effort on the part of the operator.

Attention is also directed to the fact that a single staple clinching depression may be used in place of the depressions 39. These latter are shown to fully illustrate the invention. However, the invention is not at all limited to such a construction and with other constructions of depressions the bowed portion 45 of a staple may enter between the ends of the legs of the staple without inclining such legs inwardly as shown in the drawing.

Having thus set forth the nature of my invention, what I claim is:

1. In a staple driving machine including a base, a raceway, a guide bar for guiding staples to said raceway and a plunger for driving staples through the raceway, an anvil against which staples driven through said raceway may be clinched, said anvil including a needle extending transversely of and supported by the base and having a sharpened portion laterally beyond one side thereof for ready penetration of a material on lateral movement of the base and adapted to be inserted through a piece of material to turn the end of a staple at the under side of the material to clinch the staple, a backing up member carried by the machine and against which said needle may be forced in the clinching operation, and an extension on said backing up member and comprising a guide and guard member extending along one side of the sharpened portion of the needle laterally of the base and limiting the distance the needle may casually penetrate.

2. In a staple driving machine including a base, a raceway, a guide bar for guiding staples to said raceway and a plunger for driving staples through the raceway, an anvil against which staples driven through the raceway may be

clinched, said anvil including a needle extending transversely of and supported by the base and having a sharpened portion laterally beyond one side thereof for ready penetration of a material on lateral movement of the base and adapted to be inserted through a piece of material to turn the ends of a staple at the under side of the material to clinch the staple, a rigid piece on the machine below the needle and comprising a backing up member against which said needle may be forced in the clinching operation, an extension on said backing up member and comprising a guide and guard extending along one side of the sharpened portion of the needle laterally of the base and limiting the distance the needle may casually penetrate, and said guide and guard at its outer end curved away from the sharpened end of the needle.

3. In a staple driving machine including a raceway, a guide bar for guiding staples to said raceway and a plunger operable from a normal position of rest to drive staples through the raceway, and means operable by the plunger after a driving stroke and as it returns to said normal position to force a staple from the delivery end of the raceway if one remains therein.

4. In a staple driving machine including a raceway, a guide bar for guiding staples to said raceway and a plunger for driving staples through the raceway, an arm pivoted intermediate its end to said machine, said plunger having an opening therein receiving one end of said arm whereby the plunger rocks the arm as the plunger is moved through the raceway, a dog pivoted on said arm, a spring normally holding said dog in a position tending to enter said raceway, said arm adapted as it is rocked by the plunger to shift said dog in one direction as the plunger makes its driving stroke and shift the dog in the opposite direction as the plunger makes its return stroke, and said dog adapted as it is shifted in the last direction to enter the raceway and pass through the delivery end thereof.

5. In a staple driving machine including a raceway and a plunger operable from a normal position of rest to drive staples through the raceway, means operable through the raceway by the plunger after a driving stroke and as it returns to said normal position of rest capable of forcing a retained staple from the delivery end of the raceway.

6. In a stapling machine, a pair of handles, an anvil on one of said handles, a head, a staple driving plunger in said head, means on the other handle and connected with said plunger whereby on movement of said handles toward one another said plunger is operated to drive a staple, said anvil comprising a needle extending in the direction of the breadth of the plunger and supported by the machine and extending across the end of the plunger and having a sharpened end beyond one side of the machine whereby on manipulation of the machine by its handles the pointed end of the anvil may be forced through a material and the machine moved bodily laterally to dispose the plunger at one side and the anvil at the other side of the material.

7. In a staple driving machine, an anvil, a head, means for feeding staples to said head, a plunger in said head and operable to drive a staple therefrom against said anvil, said anvil including a needle with a pointed end extending in the direction of the breadth of the plunger and extending beyond each edge of the plunger and free from its pointed end beyond one edge.

of the plunger to a point beyond the other edge of the plunger, means including a pair of connected members of which one carries said anvil and the other is connected to cause operation of said plunger on movement of said members toward one another, and said members comprising handles whereby the entire machine may be moved laterally to cause the pointed end of the anvil to penetrate a fabric and then move further to bring the anvil into position with the fabric between the anvil and the plunger.

8. In a staple driving machine including a jaw and a head having a plunger movable therein to drive a staple therefrom in the direction of the jaw, means connecting the jaw and head for movement toward and from one another, a lateral extension on one side of the jaw, a needle, means securing one end of the needle to said extension, said needle sharpened at its other end for penetration and extending between the head and jaw and normally spaced from each of them and of a length disposing its sharpened end laterally beyond the jaw and head for ready penetration of one layer of a double layer of material to permit one layer of material to enter between the needle and jaw and the other between the needle and head on relative lateral movement of the machine and material, and said needle comprising an anvil against which staples driven from the head may be clinched.

9. In a staple driving machine comprising an elongated body including a head and a base and of which the head includes means to drive staples in the direction of the base, a needle extending transversely of the machine body between the head and base and in the path of movement of a staple driven from the head, means receiving one end portion of the needle at one side of the body and supporting the needle in position extending between the head and body in spaced relation to each of them to permit of the location of material at both sides of the needle, said needle of such length as to dispose its other end beyond the other side of the machine body and having such other end sharpened and free for ready penetration of a material, said needle having staple prong turning recesses in the path of movement of the prongs of a staple driven from said head, and said needle being resilient whereby as a staple is driven against it the needle will yield to bring its intermediate recessed portion into position to be supported by the base.

10. In a staple driving machine including a raceway and a plunger operable from a normal position of rest to drive staples through the raceway, means for supplying staples to the raceway, means to operate the plunger, and means operable through the raceway after the driving stroke of the plunger capable of forcing a partially driven staple from the delivery end of the raceway.

11. In a staple driving machine including a raceway and a plunger operable from a normal position of rest to drive staples through the raceway, means for supplying staples to the raceway, means to operate the plunger, a dog, means mounting the dog on the machine, spring means

normally urging said dog to enter the raceway, and means to move said dog through the raceway after the start of the return movement of the plunger following a driving stroke whereby to have the dog force a staple from the delivery end of the raceway when the staple is not freed therefrom by the plunger.

12. In a stapling machine, a pair of handles, an anvil on one of said handles, a head, a staple driving plunger in said head, means on the other handle and connected with said plunger whereby on movement of one handle toward the other said plunger is operated to drive a staple, said anvil comprising a needle extending in the direction of the breadth of the plunger and supported by the machine and extending across the end of the plunger and having a sharpened end beyond one side of the machine whereby on manipulation of the machine by its handles the sharpened end of the anvil may be forced through a material and the machine moved bodily laterally to dispose the plunger at one side and the anvil at the other side of the material, and a backing up member carried by the machine and against which said needle is supported in a clinching operation.

13. In a staple driving machine, an anvil, a head, means for feeding staples to said head, a plunger in said head and operable to drive a staple therefrom against said anvil, said anvil including a needle with a pointed end extending in the direction of the breadth of the plunger and extending beyond each edge of the plunger and free from its pointed end beyond one edge of the plunger to a point beyond the other edge of the plunger, a backing up means against which said needle is supported in a clinching operation, means including a pair of connected members of which one carries said anvil and the other is connected to cause operation of said plunger on movement of one member toward the other, and said members comprising handles whereby the entire machine may be moved laterally to cause the pointed end of the anvil to penetrate a fabric and then move farther to bring the anvil into position with the fabric between the anvil and the plunger.

14. In a machine for stapling trouser cuffs, means for driving a staple, a member extending across the path of movement of a staple driven by said means and against which said staple may be clenched, said member being of small cross sectional area and having a free end beyond said path and shaped for piercing a layer of fabric, said member having staple clenching recesses in its inner side inwardly of its piercing end and adapted to be partly passed through a fabric to dispose its recesses at the side of the fabric opposite the staple driving means to cause clenching at the said opposite side of the fabric of the legs of a staple driven by said means, and a rigid supporting means at the outer side of said member to support the portion thereof having said recesses while a staple driven through the fabric by the first means is being clenched.

FRANK R. CURTISS.
